UNITED STATES PATENT OFFICE.

GUSTAVE B. REISBACH, OF MILWAUKEE, WISCONSIN. ASSIGNOR TO THE CUTLER-HAMMER MFG. CO., OF MILWAUKEE, WISCONSIN, A CORPORATION OF WISCONSIN.

IGNITION DEVICE.

1,096,459.

Specification of Letters Patent.

Patented May 12, 1914.

Application filed July 25, 1910. Serial No. 573,649.

To all whom it may concern:

Be it known that I, GUSTAVE B. REISBACH, a citizen of the United States, residing at Milwaukee, in the county of Milwaukee and State of Wisconsin, have invented new and useful Improvements in Ignition Devices, of which the following is a full, clear, concise, and exact description, reference being had to the accompanying drawing, forming 10 a part of this specification.

My invention relates to improvements in ignition devices for explosive engines.

It is one of the objects of my invention to provide a simple and efficient device for 15 ignition purposes arranged to be operated by electromagnets or solenoids.

My invention also has various other objects and advantages which will be herein-after clearly and fully set forth.

20 For the purpose of fully disclosing the nature and characteristic features of my invention, I shall describe the device illustrated in the accompanying drawing which embodies my invention in its preferred 25 form. Of course, my invention is not limited to the specific structure illustrated, but is susceptible of modifications.

In the accompanying drawing, Figure 1 is a longitudinally sectional view through 30 the device. Fig. 2 is a front elevation of Fig. 1. Fig. 3 is a rear end view of Fig. 1 and Fig. 4 is a diagrammatic view showing one form of circuit connection for the device.

The several parts of the device are carried by a suitable frame having a head 1 adapted to be secured by bolts 2, or other suitable means, to the cylinder head of a suitable explosive engine. Projecting from the head 1 are a pair of substantially parallel members 4, only one of the same being shown in Fig. 1. At their extremities the members 4 carry a circular member 5. The several parts of the frame may be formed integrally, and in practice said frame is preferably formed of cast iron. The frame carries a tubular member or sleeve 6 arranged between the members 4 and projecting into the end portions of said frame. For the purpose hereinafter set forth I desire to have the sleeve electrically insulated from the frame. I, therefore, prefer to provide within the end portions of the frame insulating bushings 7 and 8 through which the sleeve passes and which effectually maintain the sleeve out of contact with the frame.

The insulating bushings may be formed of any suitable material and may conveniently be formed of mica washers. The sleeve 6 is provided with a head 9 adapted to bear against the end of the insulating bushing 8 and is provided at its opposite end with a screw-threaded portion 10 carrying a nut 11 arranged to bear against the end of the insulating bushing 7. The insulating bushings 7 and 8 are arranged to bear against annular shoulders provided in the frame and, hence, when the nut 11 is turned against bushing 7, said bushings and said sleeve will be firmly secured in place in said frame. The sleeve 6 forms a bearing for a shaft or spindle 14 extending therethrough and adapted to freely turn therein. At its rear end the shaft or spindle 14 carries the movable element 15 of the sparking device. As illustrated, the member 15 is substantially S shaped and provided with suitable contacts 16 arranged to coöperate with stationary contacts 16^a carried by lugs 18 which may be formed integrally with the portion 5 of the frame. The member 15 being rigidly secured to the spindle 14 may be moved into and out of engagement with the stationary contact points to produce the desired sparking by merely oscillating said spindle within the sleeve 6.

The means which I have provided for oscillating the spindle 14 comprise solenoids 17 and 18. The two solenoids are suitably mounted on the head 1 of the frame on opposite sides of the spindle 14. The two solenoids are of the same construction, but one of the same is inverted with relation to the other. The details of construction of the solenoid 17 are clearly illustrated in Fig. 1. The solenoid 17 is mounted in a three sided magnet frame 19, said magnet frame being suitably secured to the head 1 of the supporting frame. At its lower end the solenoid is provided with a stationary plug 22 and with a movable plunger 23, both being illustrated in dotted lines. The plunger is preferably provided with a conical end adapted to fit into a correspondingly shaped cavity in the end of the plug. The plunger carries a rod 24 arranged to pass through and freely slide within the stationary plug. The parallel members of the magnet frame are provided at their extremities with apertures 25 and 26 within which is mounted a rod 27 arranged to slide 105

longitudinally. The lower end of the rod 27 is connected to the lower end of the rod 24 by a member 28 provided at opposite ends with recessed portions adapted to receive the ends of said rods, pins 30 being provided to lock said member 28 to said rods. The upper end of the rod 27 is connected in a similar manner by a member 31 to the end of the plunger 23 of the solenoid 17. With this arrangement, the plunger of the solenoid and the rod 27 move together as an integral structure, the magnet frame forming guides for the rod 27 and likewise for the plunger of the solenoid. For biasing the plunger of the solenoid in a direction away from the stationary plug, I have provided a conical spring 32 interposed between the magnet frame and the member 31 fixed to the plunger.

The structure of the solenoid 8 and the parts associated therewith are precisely like those above described and, hence, will be given the same reference characters without further description. The solenoid 18, however, is inverted with relation to the solenoid 17, and hence, upon energization of said solenoids they would tend to draw their plungers in opposite directions.

The connections between the solenoids and the spindle 14 are as follows: Upon the outer end of the spindle 14 is a cross member 33 provided at opposite ends with cylindrical lugs 34. The member 33 is preferably split to fit onto the plunger, or formed in two sections and provided with bolts or screws 35 for clamping the same to said spindle to move therewith. An insulating bushing 33^a is preferably interposed between the member 33 and said spindle to insulate the same from one another. As illustrated, this bushing is formed in two longitudinal sections arranged to form a substantially cylindrical sleeve having a flange at the end thereof. The bushing, being clamped between the member 33 and the spindle, will be firmly held in place. Mounted on the rods 27, operated by the solenoids 17 and 18 are collars 36 retained in place on said rods by pins 37. The collars 36 are provided with bifurcated portions 38 arranged to receive the extremities of the member 33 on the spindle 14. With this arrangement, when the rods 27 are moved in opposite directions by the solenoids 17 and 18 they will coöperate to move the member 33, thereby revolving the spindle 14 and rocking the movable sparking member. The collars 36 are so adjusted on the rods 27 that when said rods are moved under the influence of the springs 32 they will cause movement of the member 33 in a direction to throw the movable sparking element into engagement with the stationary contacts thereof.

For making the desired circuit connections, I have provided a pair of binding

posts 38 and 39 on each of the magnet frames and interposed between the nut 11 on the sleeve 6 and the insulating bushing 7 a conducting strip 40 carrying a binding post 41. The binding posts 38 and 39 are suitably insulated from the magnet frame while the conducting strip 40 provides an electrical connection from the binding post 41 to the sleeve 6 and thence to the shaft or spindle 14. These binding posts permit of the connections illustrated in Fig. 4, which I shall now describe.

The solenoids 17 and 18 are connected in parallel between the brush 42 of a suitable commutator or timer 43 and the conducting strip 40 which I have diagrammatically illustrated as bearing directly upon the spindle 14. The other contact brush 44 of the commutator or timer is connected to one terminal of a storage battery 45, the other terminal of the storage battery being grounded. The stationary contacts of the sparking plug are connected to a ground wire 46. The commutator or timer is provided for energizing the solenoids at the desired periods, the same being adapted to be operatively connected to any of the moving parts of the engine, or to the driven mechanism. The commutator or timer may, of course, be of any preferred construction. As diagrammatically illustrated, it is provided with a contact 47 arranged to be continuously engaged by the brush 44 and with an insulating portion 48 carrying a small contact segment 49 adapted to engage with the contact brush 42. With the circuit connections illustrated, it will be seen that the circuit of the solenoids is completed through the sparking contacts. It is, therefore, obvious that the solenoid windings will perform the same functions as would an induction coil connected in circuit with the sparking contacts to give the required spark.

The operation of the device is as follows: When the contact 49 of the commutator or timer is brought into engagement with contact brush 42, circuit is closed from the battery 45 through the solenoids in parallel to the spindle 14, thence through the contacts of the sparking device to the ground. Thereupon the solenoids respond oscillating the spindle 14 and drawing the sparking element 15 away from the stationary contacts. This results in drawing an arc or arcs between the movable sparking element and one or both of the stationary contacts to ignite the charge in the engine. Of course, as soon as the arc drawn between the contacts of the sparking device is broken, circuit through the solenoids is interrupted, whereupon, the plungers of the solenoids move under the influence of the springs 32 to return the contacts of the sparking device into engagement. In the meantime the contact 49 of the commutator or timer has been moved out

of engagement with the contact brush 42 and the solenoids will remain deenergized until the engine has completed a predetermined cycle to again bring the contacts of the commutator or timer into engagement. The same operation of the sparking device is then repeated. If perfect mechanical adjustment could be obtained, arcs would be drawn between the movable member of the 10 sparking plug and both of the stationary contacts. In practice, however, it is very difficult to obtain such mechanical perfection, and furthermore it is unnecessary to do so. Hence, in actual operation, probably, 15 only one spark would be formed in the majority of instances. However, by providing two contact points the wear on the contact surfaces would be equally divided between said points of contact, thereby maintaining the life of the sparking plug for a 20 much longer time than if only one contact point were provided.

Having thus described my invention what I claim as new and desire to secure by Letters Patent, is:

1. In combination, a supporting member, a pair of magnet frames mounted thereon, solenoids mounted in said magnet frames and having movable plungers adapted to be 30 magnetically attracted in relatively opposite directions, a spindle revolvably supported by said supporting member between said solenoids, a contact fixed to said spindle and operative connections between said spindle 35 and the plungers of said solenoids for causing said solenoids when energized to co-operate in revolving said spindle to oscillate said contact in one direction.

2. In combination, a supporting member, 40 a pair of magnet frames mounted thereon, solenoids mounted in said magnet frames and having movable plungers adapted to be magnetically attracted in relatively opposite directions, a spindle revolvably supported by said supporting member between said solenoids, a contact fixed to said spindle, operative connections between said spindle and the plungers of said solenoids for causing said solenoids when energized to 45 co-operate to revolve said spindle to oscillate said contact in one direction and means biasing the plungers of said solenoids in an opposite direction to that in which they are magnetically moved to cause the same to 50 oscillate said contact in an opposite direction when said solenoids are deenergized.

3. In combination, a supporting member, 60 a pair of magnet frames mounted thereon, solenoids mounted in said frames and having movable plungers adapted to be magnetically attracted in relatively opposite directions, a spindle revolvably supported by said supporting member between said solenoids, a contact fixed to said spindle and 65 operative connections between the plungers

of said solenoids and said spindle, including rods movable with said plungers and working in guides in the magnet frames, for causing said solenoids to coöperate to oscillate said spindle and said contact in one direction. 70

4. In combination, a supporting member, a pair of magnet frames mounted side by side thereon, solenoids mounted in said frames and having movable plungers adapted to be magnetically attracted in relatively opposite directions, a spindle revolvably supported by said supporting member between said solenoids, a contact fixed to said spindle, operative connections between the plungers of said solenoids and said spindle, including rods movable with said plungers and working in guides in the magnet frame for causing said solenoids to coöperate to oscillate said spindle and said contact in one direction, and coiled springs surrounding the plungers of said solenoids and arranged to bias said plungers in an opposite direction to that in which they are moved by said solenoids. 80

5. In combination, a supporting member, a pair of solenoids mounted side by side thereon and having movable plungers adapted to be magnetically attracted in relatively opposite directions, a pair of rods external to said solenoids, each being connected to the plunger of one of said solenoids to move therewith, stationary guides for said rods, a spindle revolvably supported by said supporting member between said solenoids, a contact fixed to said spindle and operative connections between said spindle and said rods for causing said spindle and said contact to be oscillated in one direction when said solenoids are energized. 90

6. In combination, a supporting member, a pair of solenoids mounted side by side thereon and each having a movable plunger, said plungers being magnetically attracted in opposite directions, a pair of rods external to said solenoids, each being connected to the plunger of one of said solenoids to move therewith, stationary guides for said rods, a spindle revolvably supported by said supporting member between said solenoids, a contact fixed to said spindle, operative connections between said spindle and said rods for causing said spindle and said contact to be rotated in one direction when said solenoids are energized and means tending to restore said plungers to normal position to rotate said spindle and said contact in an opposite direction when said solenoids are deenergized. 100

7. In combination, a supporting member, a pair of solenoids mounted side by side thereon and having movable plungers adapted to be magnetically attracted in opposite directions, each of said plungers having portions projecting from opposite ends of its 110 115 120 125 130

operating winding, a rod external to each of said solenoids and rigidly connected to its plunger at opposite ends thereof, stationary guides for said rods, a spindle revolvably supported by said supporting member between said solenoids, a contact fixed to said spindle, a cross member secured to said spindle and devices carried by said rods for engaging the opposite ends of said cross member to cause said solenoids when energized to co-operate in oscillating said spindle and said contact in one direction.

8. In combination, a supporting member, a pair of solenoids mounted side by side thereon and having movable plungers adapted to be magnetically attracted in opposite directions, each of said plungers having portions projecting from opposite ends of its operating winding, a rod external to each of said solenoids and rigidly connected to its plunger at opposite ends thereof, stationary guides for said rods, a spindle revolvably supported by said supporting member between said solenoids, a contact fixed to said spindle, a cross member secured to said spindle, devices carried by said rods for engaging the opposite ends of said cross member to cause said solenoids when energized to co-operate in oscillating said spindle and said contact in one direction, and means biasing the plungers of said solenoids to cause the same to oscillate said spindle and said contact in an opposite direction when said solenoids are deenergized.

35 9. In combination, a supporting member, a pair of magnet frames mounted side by side thereon, a solenoid mounted in each of said magnet frames, said solenoids having movable plungers adapted to be magnetically attracted in opposite directions, each of said plungers having portions projecting from opposite ends of its operating winding, a longitudinally movable rod slidably mounted in each of said magnet frames and disposed substantially parallel to the plunger of the solenoid mounted therein, each of said plungers being rigidly connected at opposite

ends to one of said rods to cause the same to move therewith, a spindle revolvably supported by said supporting member between 50 said solenoids, a contact fixed to said spindle, a cross member fixed to said spindle and devices carried by said rods for engaging the extremities of said cross members to cause said solenoids when energized to oscillate 55 said spindle and said contact in one direction.

10. In an ignition device for explosive engines, in combination, a supporting frame, a spindle revolvably mounted therein, an oscillating contact fixed to said spindle, a pair of magnet frames mounted on the head of said supporting frame and arranged in substantially parallel relation on opposite sides of said spindle, a solenoid winding mounted in 65 each of said magnet frames, a stationary core and a movable plunger within each of said windings, the plunger of each winding having an extension passing through its corresponding stationary core a sliding rod arranged in parallel relation with each of said plungers and connected to move therewith, each of said rods working in guides on one of the magnet frames, a coil spring surrounding the plunger of each solenoid and 70 interposed between the magnet frame and a part fixed to the plunger, a cross member fixed to said spindle and devices fixed to said rods for engaging the opposite ends of said cross member, one of said solenoids being inverted with relation to the other to cause said solenoids when energized to co-jointly oscillate said contact member in one direction, said springs biasing the movable parts of said solenoids in a direction to return said 75 contact member to normal position upon deenergization of said solenoids.

In witness whereof, I have hereunto subscribed my name in the presence of two witnesses.

GUSTAVE B. REISBACH.
